CLOTH ROLL SUPPORT DEVICE

John Rinne, Staten Island, N. Y., and Everett H. Ashton, Allston, and Robert G. Mallard, Hopedale, Mass., and Francis Gerard Lake, New York, N. Y., assignors, by mesne assignments, to Steel and Alloy Tank Company, Newark, N. J., a corporation of New Jersey

Original application April 2, 1947, Serial No. 739,004, now Patent No. 2,518,185, dated August 8, 1950. Divided and this application February 3, 1950, Serial No. 142,201

2 Claims. (Cl. 139—308)

1

The present invention relates to a cloth roll take-up mechanism for looms and is a division of application Serial No. 739,004, filed April 2, 1947, now Patent No. 2,518,185.

It is the principal object of this invention to provide a new and improved cloth roll supporting means which effects automatic lowering of the cloth roll axis as the diameter of said roll increases, while maintaining said roll in friction drive contact with the take-up roll, which permits selective adjustments in the pressure with which said cloth roll contacts said take-up roll for drive action, which permits a full cloth roll to be easily removed therefrom and an empty cloth roll to be easily mounted thereon, and which permits easy manipulation of the cloth roll up or down with respect to the take-up roll.

Various other objects of the invention will be apparent from the following particular description, and from an inspection of the accompanying drawings, in which:

Fig. 1 is a front view of the left-hand side of a loom embodying the features of the present invention, certain parts of said loom not related to the present invention being absent from the view for the purpose of clarity;

Fig. 2 is a section of the right-hand side of the loom looking outwardly, taken approximately along the lines 2—2 of Fig. 3, and showing in the main the cloth roll structure and the support therefor at the beginning of cloth winding operation;

Fig. 3 is a section of the loom taken approximately along the lines 3—3 of Fig. 2;

Fig. 4 is a detail section of the cloth roll ratchet taken along the lines 4—4 of Fig. 3; and

Fig. 5 is a detail section of the cloth roll tension spring adjustment collar taken along the lines 5—5 of Fig. 3.

Referring to the drawings, and especially to Fig. 1, the loom frame may be of the conventional type, but is desirably of the improved form shown in copending application, Serial No. 691,237, filed August 17, 1946, now Patent No. 2,533,128. In this improved type of loom, instead of the conventional loomsides, each with a single frame web, each loomside comprises a pair of parallel webs 10 and 11 rigidly interconnected by suitable girts and bracing members.

Mounted near the front section of the loom is the take-up motion comprising a take-up roll 12 supported on the loomsides and covered with sandpaper or similar rough surfaced material adapted to frictionally grip the cloth A after it is formed and advance it towards the cloth roll

2

13. The cloth roll 13 is pressed into contact with the take-up roll 12 and is frictionally driven thereby to wind the cloth around said roll 13. The take-up roll 12 has secured to the ends thereof gudgeons journalled in suitable bearings on the inside frame webs 10. One of the gudgeons on the left-hand loomside has secured thereto between the two frame webs 10 and 11 a gear 16 by which the take-up roll 12 is continuously driven as the cloth is formed. The take-up roll gear 16 is driven from the crank shaft of the loom (not shown), which extends parallel to the axis of the take-up roll 12, and which drives through a pair of intermeshing gears (not shown), a short pick cam shaft below said crank shaft on the left-hand side of the loom. On the pick cam shaft is connected a bevel gear meshing with a bevel gear on a drive shaft. Between the drive shaft and the take-up roll gear 16, is a take-up gear transmission 25. The transmission 25 and the associated mechanisms are not the basis of the claims of this application and will not be described particularly as they are fully shown and described in said parent application Serial No. 739,004.

A pressure applying means 200 is provided for maintaining the cloth A in controllable pressure gripping contact with the periphery of the take-up roll 12, to afford effective advancement of the cloth A towards the cloth roll 13. The pressure applying means 200 is fully disclosed in said parent application Serial No. 739,004 and will not be gone into in detail since it does not form the basis for the claims of this application. The pressure means 200 includes a pressure roll extending in front of the take-up roll 12 and along substantially the full length thereof, and supported at its ends in a pair of upright arms mounted at their lower ends in pivots secured to the inner sides of the inside frame webs 10. To press the roll of pressure applying means 200 against the take-up roll 12, pressure applying means 200 includes a cam arrangement for moving the pressure roll about its pivot supports and for holding said supports in any selected position.

The full cloth roll 13 may be lowered out of drive engagement with the take-up roll 12, and the cloth cut-off, to permit said cloth roll to be removed from the loom without moving the pressure roll 200 out of contact with said take-up applying means. The cloth will therefore remain threaded in position around the take-up roll 12 while a new empty cloth roll is being set

up on the loom; thus the cloth roll 13 may be removed while the loom is running.

The cloth roll 13 is maintained in friction drive contact with the lower section of the take-up roll 12 to rotate said cloth roll at the speed necessary to wind the cloth therearound. For supporting the cloth roll 13 in a manner to compensate for the progressive increase in its diameter, as the cloth winding operation proceeds, there is provided a cloth roll support axle 240 mounted at its ends in bearings 241 fixed to the inside frame webs 10. Supported on the axle 240 for angular movement thereabout is a cloth roll support frame 242 comprising a pair of arms 243 and 244 having respective hubs 245 embracing the axle 240 with a snug rotative fit, and rigidly interconnected by means of a cross frame piece 246. The frame piece 246 is preferably of circular segmental cross-section, and may comprise a segment of a pipe welded to the support arms 243 and 244, and extending concentrically of the roll axle 240.

The outer roll supporting end of each arm 243 and 244 is provided with a notch 247 for receiving the gudgeon 250 of a cloth roll shaft 251. The cloth roll shaft 251 includes at its ends the gudgeons 250. The cloth roll shaft 251 is thereby free to rotate in the cloth roll support arms 243 and 244, and is rotated by the friction drive engagement of the take-up roll 12 with the cloth wound around said cloth roll shaft 251.

The cloth roll support arms 243 and 244 are urged angularly upwardly about the axle 240, to maintain the cloth roll 13 in frictional contact with the take-up roll 12 under yieldable spring pressure. For that purpose, there is provided at each end of the cloth roll support axle 240 a torsion spring 260 encircling said axle, and having one end engaging a lug 261 fixed directly to the axle 240, and having its other end engaging a lug 262 fixed to the corresponding hub 245. The coil spring 260 is torsionally stressed by the two lugs 261 and 262, to urge the cloth support arms 243 and 244 in a counterclockwise direction, as viewed in Fig. 2.

At the beginning of the winding operation, when the cloth roll support arms 243 and 244 are in their uppermost position shown in Fig. 2, the springs 260 are torsionally stressed to their lower values. As the diameter of the cloth roll 13 increases, the cloth support arms 243 and 244 are moved angularly clockwise about the axle 240, thereby increasing the torsion stress on the springs 260. The springs 260 thereby automatically compensate for the progressive increase in the weight of the cloth roll 13, so that effective friction driving engagement of said cloth roll with the take-up roll 12 is maintained throughout the cloth winding operations.

Means are provided for adjusting the torsion stress of the springs 260. To that end, there is keyed to each end of the axle 240 a ratchet wheel 265. Pivotal mounted on the inner side of the corresponding inside frame web 10 is a pawl 266 supported on a pivot stud 267 on said frame web, and cooperating with the teeth of the ratchet wheel 265. Also keyed to each end of the axle 240 near the ratchet wheel 265 is a spring adjusting collar 268, desirably comprising two sections secured together by means of studs 270, as shown in Figs. 3 and 5. The collar 268 is of hexagonal shape to receive a suitable turning tool, and serves not only as means by which the torsion stress on the springs 260 may be varied through rotation of the axle 240, but also as a

means for spacing the cloth roll supporting frame structure 242 from the inside frame webs 10.

When it is desired to increase the torsion stress on the spring 260, the collar 268 at each end of the axle 240 is rotated in a direction to permit the corresponding ratchet wheel 265 to ride idly past its pawl 266. The detent engagement of the pawl 266 with the teeth of the ratchet wheel 265 locks the axle 240 against reverse rotation, and thereby prevents release of the adjusted torsion stress on the corresponding spring 260.

For lowering the cloth roll 13 by hand out of friction drive engagement with the take-up roll 12, as for example, when it is desired to remove

15 a full cloth roll and to replace it by an empty one, one of the cloth roll support arms 243 has a handle extension 275. To maintain the cloth roll 13 in any selected elevational position out of engagement with the take-up roll 12 and

20 against the action of the springs 260, there is secured to the inner face of one of the inside frame webs 10 adjacent to the cloth roll support arm 243 an arcuate ratchet bar 276 substantially concentric with the cloth roll support axle 240,

25 and having a series of teeth 277 separated by spaces or notches 278. The outer upward edge of each tooth 277 has a bevelled surface 280 for the purpose to be made apparent. Aligned with notch 247, rigid with the cloth roll support arm 243, is a pivot stud 281. Supported on said stud

30 for rotation thereabout is a pawl 282 adapted to ride over the outer surface of the ratchet bar 276, and urged into contact with said ratchet bar by means of a torsion spring 283. The pawl

35 282 has a bevelled cam surface 284 at its outer end, which is adapted to ride idly over the bevelled edges 280 of the ratchet teeth 277 as the cloth roll support arms 243 and 244 are swung downwardly about the cloth roll support axle 240,

40 so that the downward movement of said support arms is effected without interference from the ratchet bar 276. The upward movement of the cloth roll support arms 243 and 244 is, on the other hand, prevented by the locking engagement

45 of the pawl 282 with the ratchet teeth 277.

To release the pawl 282 from locking engagement with the ratchet bar 276, and thereby to permit the cloth roll support structure 242 to be raised upwardly, the pawl 282 has a handle extension 290 comprising a section 291 rigid with the pawl 282, and a section 292, which normally hangs downwardly from said handle section 291

50 as shown in dot and dash lines in Fig. 2, and which may be latched into locking engagement with said handle section 291 to form a horizontal handle extension therefor, as shown in full lines, when it is desired to render the pawl 282 inoperative. The handle section 292 has at one end a fork 293 flanking the handle section 291, and

55 carrying a pair of pins 294 and 295 between the branches thereof. The handle section 291 has an elongated slot 296 for receiving the pin 294, and the outer end of said handle section 291 has a notch 297 for receiving the other pin 295. In

60 normal inoperative position, the handle section 292 extends downwardly, as shown in dot and dash lines in Fig. 2, with the pin 294 resting at the bottom of the slot 296 in the handle extension 291. When it is desired to render the pawl 282

65 inoperative, the handle section 292 is swung counterclockwise from the depending position shown in dot and dash lines in Fig. 2, until said section 292 is in alignment with the outer end part of the handle section 291. In this position, the handle section 292 is moved inwardly to the left to bring

the pin 295 into the base of the notch 297 of the handle section 291, and to bring the other pin 294 into the lefthand upper end of the elongated slot 296. In this position, the two handle sections 291 and 292 will be locked in position for clockwise rotation of the handle 290. The clockwise rotation of the handle 290 will move the pawl 282 out of the path of the ratchet bar 276. While the pawl 282 is in this released position, the cloth roll support structure 242 can be raised through the action of the torsion springs 260 without interference from the ratchet 276 and the pawl 282.

To effect the upward movement of the cloth roll support structure 242 through the action of the springs 260 at controlled rates, the pawl supporting handle section 291 pivotally carries a brake shoe 298 lined with suitable braking material, and adapted to be moved into braking engagement with the ratchet bar 276, which for that purpose, serves as a brake drum. By angular manipulation of the handle 290 about the pivot stud 281, it is possible to move the brake shoe 298 towards and away from the brake drum section of the ratchet bar 276, and thereby control the ascent of the cloth roll 13 towards the take-up roll 12 under the action of the torsion springs 260.

As many changes can be made in the above apparatus, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. In a take-up mechanism for a loom, a cloth roll, means supporting said cloth roll for movement towards and away from driven position, spring means urging said cloth roll towards said driven position, a fixed brake frame plate extending substantially parallel to said movement, and having ratchet teeth, a pawl carried by said cloth roll and adapted to cooperate with said ratchet teeth to lock said cloth roll against movement 45

towards said driven position in opposition to the action of said urging means, while permitting said cloth roll to move away from its original cloth roll driven position as the diameter of said cloth roll increases during cloth winding operations, a handle for moving said pawl in and out of co-operative position with respect to said ratchet teeth, a brake shoe carried by said cloth roll and movable by said handle towards and away from said brake frame plate, to control the movement of said cloth roll towards driven position under the action of said urging means.

2. In a take-up mechanism for a loom, a cloth roll, means supporting said cloth roll for movement through an arcuate path towards and away from driven position, spring means urging said cloth roll towards said driven position, a fixed brake plate extending substantially parallel to said path of movement and provided with ratchet teeth spaced along its length, a lever, having a handle extension, pivoted intermediate its ends on said cloth roll, said lever including a pawl on one side of its pivot point adapted to cooperate with said ratchet teeth to lock said cloth roll against movement towards said driven position, said lever also including a brake shoe on the other side of its pivot point adapted to frictionally engage said brake plate to reduce the urging action of said spring means, and spring means biasing said lever 30 to carry said pawl towards said ratchet teeth.
